SETTS, A CORPORATION OF NEW JERSEY.

MULTI-INDORSEMENT-RESTRICTING DEVICE FOR VOTING-MACHINES.

No. 846,014.

Specification of Letters Patent.

Patented March 5, 1907.

Application filed October 15, 1906. Serial No. 338,907.

To all whom it may concern:

Be it known that I, WILLARD M. DELAVAN, a citizen of the United States, residing at Pittsfield, county of Berkshire, State of Massachusetts, have invented a new and useful 5 Multi-Indorsement-Restricting Device for Voting-Machines, of which the following is a specification.

This invention has for its object to provide 10 restricting means operative in connection with the voting members of a voting-machine in group voting to prevent a plurality of votes being cast for a candidate who has been nominated by a plurality of parties— 15 that is, has received multi-indorsement.

The term "group voting" is used to describe a style of voting which permits voters to vote for more than one candidate for the same office—as, for example, in voting for a 20 plurality of members of a board, commission, court, or a delegation of two or more members. Suppose as an illustration that four members of a board are to be elected and that four political parties have each made 25 four nominations for the four positions to be filled. Specifically the special grouping mechanism used is not of the essence of the present invention. It is sufficient for the purposes of this specification to state that any 30 grouping mechanism applicable to a voting-machine whose voting members comprise oscillatory shafts may be used and that the function of grouping mechanism broadly is to so connect up the voting members corre- 35 sponding to the names of candidates to be voted for in a group that a voter may cast all his votes—in the present instance four—for the nominees of one party or may cast one vote for one nominee of each party—in brief, that 40 a voter may cast any number of votes up to four, and may cast one vote each for any four he may select out of the sixteen candidates in nomination. This is ordinary group voting.

45 My present invention is applicable to a voting-machine or a portion thereof set up for group voting when one or more of the candidates nominated has received multi-indorsement—that is, has been nominated 50 for the same office by two or more political parties; and the object of the invention is to prevent what is termed in English voting

"plumping"—that is, the casting by a voter of a plurality of votes for one candidate.

The present invention, in connection with 55 suitable grouping mechanism, leaves the voter free to cast one vote each for any four of the sixteen candidates nominated, but only one vote for any candidate no matter how many indorsements he may have received.

With this end in view I have devised the novel restricting device which I will now describe, referring to the accompanying drawing, forming a part of this specification, and 65 using reference characters to indicate the several parts.

Figure 1 is a rear elevation of a portion of a voting-machine—in the present instance a Triumph voting-machine—illustrating the 70 voting and counting mechanism, and in connection therewith my novel restricting device; Fig. 2, a horizontal section of the front plate and standards of a voting-machine, showing the voting and counting mechanism 75 in plan with my novel restricting device applied thereto; Fig. 3, an end elevation, on an enlarged scale, of one of the rocker-arms detached, the locking-key being shown in place; Fig. 4, a plan view corresponding therewith, 80 the locking-key being removed; and Fig. 5 is a detail elevation illustrating the operation of a series of rocker-arms in connection with the restricting flexible member.

I have illustrated an arrangement of a vot- 85 ing-machine in which the names of party candidates are placed in vertical columns or lines and the names of the candidates for the same office are placed in horizontal lines. It should be understood, however, that the 90 present invention is equally applicable to a machine in which the reverse arrangement is adopted—that is, to a "horizontal" ma- 95 chine, so called, in which the names of the party candidates are placed in horizontal lines and the names of the candidates for the same office are placed in vertical columns or lines.

10 denotes the front plate of a voting-ma- 100 chine, and 11 standards back of the front plate.

50 denotes voting members as a whole; each voting member comprising a shaft 12, an operating-lever 13, a locking-lug 14, and a

counter-dog 15. The shafts of the voting members are journaled in the front plate and in bearings 16, which extend from the standards, the locking-lugs lying between the 5 front plate and the standards and the counter-dogs lying contiguous to the ends of bearings 16. The voting-member shafts are extended inward beyond the counter-dogs for a purpose presently to be explained. 10 Lying intermediate the front plate and the standards and corresponding with each horizontal line of voting members is a wedge-bar or resetting-slide, (indicated by 17,) a restricting-bar, (indicated by 18,) and between said 15 bars a flexible member, in the present instance a chain, (indicated by 19.) One end of each flexible member is connected to a fixed vertical bar 20, and the other end is connected, by means of a turnbuckle 21, to a movable plate 22, lying between vertical plates 23, which together comprise what is termed the "grouping-column."

24 denotes counters carried by counter-bars 25. The shaft 26 of each counter carries a disk 27, eccentrically placed thereon, and each disk is provided with a pin 28, which passes into a hole 29 in the corresponding counter-dog when the latter is moved to the counting position by the operation of 25 voting. In practice the counter-bars, carrying the counters, have imparted thereto an endwise and lateral rotary oscillation by means of exit mechanism and connections, (not shown,) which are operated by the voter 30 as he leaves the machine, whereby each vote cast by operation of a voting member is 35 counted by the corresponding counter. 30 denotes party-bars, the operation of which causes an entire party vote to be cast by a 40 single voting operation.

In group voting, as already stated, the voter is permitted to vote for more than one candidate for the same office. It not infrequently happens, however, that a candidate comprising one of a group of candidates has been nominated by a plurality of parties, and his name therefore would appear in two or more party-columns. With grouping mechanism as ordinarily constructed should this 45 condition arise a voter would be able to cast two votes for a candidate who had received double indorsement, three votes for a candidate who had received triple indorsement, and so on. 50

55 In order to prevent the possibility of any voter casting more than a single vote for a candidate no matter by how many parties said candidate may have been placed in nomination, I have devised the novel multi-indorsement-restricting device, which I will 60 now describe. As already stated, the voting-member shafts are extended beyond the counter-dogs.

65 31 denotes rocker-arms, which are rigidly secured, as by keys, to the inner ends of the

voting-member shafts in the horizontal line corresponding with the office for which a candidate has received multi-indorsement. This rocker-arm carries at its ends pins 32, which are shown as provided with rollers 33. 70

34 denotes a restricting flexible member—in the present instance a metallic strip—which passes under one and over the other pin of each rocker-arm in a horizontal line. One end of the restricting flexible member is 75 shown as connected to a screw-pin 35, which is adapted to engage any one of a series of holes 36 in one of the vertical plates 23, and the other end as connected to a head 37 upon a screw 38, which is adapted to engage 80 either of a series of holes 39 in a vertical angle-plate 40. The screw passes freely through the holes in the angle-plate and is adjusted in and out by means of a nut 41, which bears against the angle-plate, said nut 85 being set after adjustment by means of a set-nut 42. It will of course be understood that 90 it is immaterial to what portions of the machine the ends of the restricting flexible member are connected.

In practice all of the voting-member shafts that are subject to grouping are extended beyond the counter-dogs and are provided at their inner ends with rocker-arms, which in regular voting and in ordinary group voting 95 have no function. In case a candidate in a group receives multi-indorsement—for example, is nominated by two or more parties for the same office—a restricting flexible member is placed in position to coöperate 100 with the rocker-arms in that horizontal line. Having placed the restricting flexible member in position, it is adjusted by means of nut 41 to give to said restricting flexible member just sufficient slack to permit one voting member 105 in that horizontal line to be operated, as clearly indicated in Fig. 5, so that should another voting member in that horizontal line be operated the slack in the restricting flexible member would be taken out from the 110 place where it was placed by the voting member first operated and would be put in a new place by the operation of the second voting member, thereby unvoting the first vote cast.

It should be understood that in setting up 115 the machine the name of the multi-indorsed candidate would be placed in the same horizontal line in each party-column. As shown in the drawing, the restricting flexible member may be easily changed from one horizontal 120 line of voting members to another. It will of course be understood that the principle is the same whether the multi-indorsed candidate receives a double, triple, or quadruple indorsement. In the present instance 125 I have illustrated four party-columns only; but it not infrequently happens that there are more than four party-columns, and it might happen that a candidate in group voting received more than a quadruple in- 130

dorsement. My novel restricting device, however, would prevent more than one vote being cast for any candidate no matter by how many parties he might have been nominated for the same office. Should it happen that two candidates in a group to be voted for should receive multi-indorsement, the names of these candidates would be placed in different horizontal lines of voting members and a restricting flexible member would be placed in position to coact with each of said horizontal lines.

In order that the operation of my multi-indorsement - restricting device may be clearly understood, I will repeat that it is only used in group voting and that in group-voting with the type of machine illustrated the flexible members 19 in the group are all slackened, so as to permit all of the votes for the group of candidates to be cast in one horizontal line if desired. This construction is perfectly operative and meets all the requirements of group voting, unless one or more of the candidates has received multi-indorsement—that is, has been nominated by two or more political parties. In that event the name of the multi-indorsed candidate is placed a corresponding plurality of times in the same horizontal line in the proper party-columns and a restricting flexible member is placed in position to coöperate with the voting members of that horizontal line, the said restricting flexible member when properly adjusted effectually preventing more than one vote being cast for the multi-indorsed candidate.

Having thus described my invention, I claim—

1. In a voting-machine, the combination with voting members and a flexible member engaged thereby, of rocker-arms carried by the voting members, pins on the rocker-arms, and an auxiliary flexible member passing

under one pin and over the other on each rocker-arm, substantially as described, for 45 the purpose specified.

2. In a voting-machine, the combination with voting members and a flexible member engaged thereby, of rocker-arms carried by the voting members, pins on the rocker-arms, an auxiliary flexible member passing under one pin and over the other on each rocker-arm, and means for adjusting said flexible member to produce sufficient slack therein to just permit the operation of one 50 voting member in a line, so that when a second voting member in that line is operated the vote cast by the operation of the first voting member will be unvoted.

3. In a voting-machine, the combination 60 with voting members and a flexible member engaged thereby, of rocker-arms carried by the voting members, pins on the rocker-arms, an auxiliary flexible member passing under one pin and over the other on each 65 rocker-arm, and detachable and adjustable means for securing the ends of said auxiliary flexible member.

4. In a voting-machine, the combination with voting members and a flexible member 70 engaged thereby, of rocker-arms carried by the voting members, pins on the rocker-arms, an auxiliary flexible member passing under one pin and over the other on each rocker-arm, a removable pin to which one 75 end of said auxiliary flexible member is connected and a removable screw with an adjusting-nut to which the other end of said flexible member is connected.

In testimony whereof I affix my signature 80 in presence of two witnesses.

WILLARD M. DELAVAN.
